UNITED STATES PATENT OFFICE.

EMIL J. FRANCK, OF PHILADELPHIA, PENNSYLVANIA.

WELT ATTACHMENT FOR KNITTING-MACHINES.

1,374,496.

Specification of Letters Patent. Patented Apr. 12, 1921.

Application filed February 18, 1919. Serial No. 277,847.

To all whom it may concern:

Be it known that I, EMIL J. FRANCK, a citizen of the United States, residing at Philadelphia, in the county of Philadelphia and State of Pennsylvania, have invented a certain new and useful Welt Attachment for Knitting-Machines, of which the following is a specification.

The principal object of the present invention is to provide a transferrer, which is a means for taking stitches off the needles by their wale loops, and subsequently putting the wale loops onto the needles in the manufacture of welts on stockings and the like, and which shall provide ample space for the passage of a needle even if the parts are slightly out of time, and which can be readily made and is strong and reliable in action.

20 The invention will be claimed at the end hereof but will be first described in connection with the embodiment of it chosen for illustration in the accompanying drawings forming part hereof and in which—

25 Figures 1 and 2, are top or plan views illustrating parts of a welt attachment equipped with transferers embodying features of the invention and showing the same in different positions.

30 Fig. 3, is a vertical section of the same, and

Fig. 4, is a top or plan view of one of the parts of a transferer.

In the drawings 1, is a dial or carrier arranged centrally of the circle of needles 2, and provided with grooves 3, formed between ribs 4. 5, is a transferer part or member provided at one end with a hook 6, and having its shank 7, off-set to one side of the plane of the hook. Each transferer consists of two of these parts 5, arranged with their hooks face to face and with their shanks in adjoining grooves 3, so that parts of adjacent transferers are disposed in adjoining grooves.

The transferers are projected as shown in Fig. 1, and retracted as shown in Fig. 2, by means of well understood mechanism, not shown, which may operate upon butts 8, projecting from the transferers, and the dial 1, is subjected to slight turning movement to line the transferers with either the needles 2, or the spaces between them. When the transferers are alined with the spaces between the needles the transferers are projected and retracted and their hooks take wale loops and hold them while the material for the welt is made. Then the dial is turned to aline the transferers with the needles and when the transferers are projected the needles work through them and take the loops from them. Here one advantage of this invention may be emphasized and it is that the space between the parts of the transferers extends all the way to the dial so that there is no danger of the needles striking the transferers even if the movement of the parts be out of time. When the transferers are retracted the needles pass between the parts at the hook portions thereof. Evidently the parts of the transferers are easily manufactured and assembled in the grooves, and when assembled, the transferers are strong and reliable.

75 What I claim is:

A welt attachment for knitting machines comprising the combination of a grooved dial or carrier, and transferers each consisting of two parts whereof each is provided with a hook and with an off-set shank, and the hooks of each of the parts of a transferer arranged face to face and the shanks of each of the parts of a transferer arranged in different and adjoining grooves whereby space is provided between the parts of the transferers all the way to the dial, substantially as described.

EMIL J. FRANCK.
